UNITED STATES PATENT OFFICE.

HERMAN STUKE, OF HOLLIS, NEW YORK, ASSIGNOR, BY MESNE ASSIGNMENTS, TO
R. HOE AND CO., INC., OF NEW YORK, N. Y., A CORPORATION OF NEW YORK.

GUARD FOR PRINTING CYLINDERS AND THE LIKE.

Application filed March 28, 1922. Serial No. 547,396.

To all whom it may concern:

Be it known that I, HERMAN STUKE, a citizen of the United States, residing at Hollis, county of Queens, and State of New York, have invented certain new and useful Improvements in Guards for Printing Cylinders and the like, fully described and represented in the following specification and the accompanying drawings, forming a part of the same.

This invention relates to certain improvements in safety devices intended particularly for use with printing machine cylinders.

It is the especial object of the present invention to provide a safety device so located relatively to the form and impression cylinders of a printing machine as to effectively prevent the pressman from getting his hand between running cylinders, the safety guard being mounted so that it may be readily moved out of its normal position when it is necessary for the pressman to have access between the cylinders, as for instance, when running a web therebetween.

It is a further object of the invention to mount the guard so that when it is moved out of normal position it may be caused to contact with a switch controlling the motor driving the printing couple with which the guard is used so that when the guard is moved out of guard position the press will be stopped.

It is a further object of the invention to produce a simple and durable construction and one which can be readily manipulated to and from guarding position by a pressman without unnecessary loss of time.

With these and other objects not specifically referred to in view, the invention consists in certain novel parts, arrangements and combinations, which will be described in detail in connection with the accompanying drawing, and the novel features thereof then pointed out in the claims hereunto annexed.

In these drawings—

Figure 1 is a partly broken away side elevation of so much of a printing machine as is necessary for an understanding of the invention, two printing couples being illustrated and the guard being shown in normal position.

Figure 2 is a view similar to Fig. 1, showing the guard in the position it assumes when moved to give access to the cylinders,

and the relation of the switch mechanism to the guard whereby the switch may be operated by the guard.

Figure 3 is a detail sectional plan view of one end of the guard looking in the direction of the arrow 3 in Fig. 1, showing one arrangement for mounting the guard.

Referring now to these drawings, the invention has been illustrated as employed with two printing couples arranged in pairs and including form cylinders 1, 1^a, and impression cylinders 2, 2^a, mounted on shafts 3 suitably supported in frames 4, the form cylinders being inked by the usual rolls 5. While only two printing couples are shown, it will be understood that the guard will be provided at any desired points in the press where it may be necessary or desirable.

In the particular construction illustrated one guard is employed for each printing couple, being shaped and located so as to lie, when in normal position, close to the periphery of both form and impression cylinders of the couple so as to guard both the cylinders. The guard will be mounted so that it can be readily moved to and from normal position, and in the best constructions, this movement will be a swinging movement. In the particular construction illustrated, the guard comprises a heavy plate of metal having two side members, 6 and 7 which may be integral and form in effect a V, the sides of the V lying close to the peripheries of the form and impression cylinders. This guard plate is pivotally mounted so that it can be swung toward and from normal position on a pair of arms 8, one of which is shown, these arms being pivoted on studs 9 secured to the side of the frames of the machine. These arms have turned ends 10 to which one side, as side 6, of the plate is secured at its outer ends, the plate thus being movable with the arms. Stops 11 are secured in the machine frame, the lower side of the arms abutting against these stops when the parts are in normal position, thus limiting the downward movement of the plate and holding it in its correct relation to the periphery of the printing cylinders.

In the best constructions, and in constructions where the cylinders are motor driven, means are provided whereby the plate when in its raised position will automatically cut

off the motor so as to stop the running of the couple. In the particular construction illustrated there is provided a pair of switches of the ordinary push type marked 5 12, 13, mounted in the frame 4, before referred to, and being in a circuit with the driving motor 130, a controlling circuit to the motor being indicated by the wires 131, 132, it being understood that in the movement of the push switches through the circuit shown "cuts out" or stops the motor. Power is transmitted from the motor to the operative parts of the press in any suitable manner the gearing not being shown as not necessary for an understanding of the invention. One of these switches, as switch 12, is mounted so as to be operated by the guard used with cylinders 1, 2, the other switch 13 is mounted so as to be operated by 15 the guard employed with cylinders 1^a and 2^a. As the guard is thrown to raised position, as indicated in Fig. 2, the edges of the plates contact with the switches and throws the motor out, thus stopping the operation of 20 the couples.

With this construction the pressman may readily and quickly, without loss of time, raise or lower the guard, it being unnecessary to unfasten the guard in any way, the 25 guard being simply swung on its pivot. At the same time the swinging movement of the guard operates the push switches and throws off the motor and automatically stops the running of the press until the pressman 30 again manipulates the switches to throw the motor in, after the guard has been swung down. With this construction, therefore, the pressman is well guarded from injury and does not have to lose any time in manipulating the guard.

While the invention has been shown in its best form, it will be understood that certain changes and variations in the form of the guard and means for mounting it in operative relation of the press cylinders may be employed without departing from the invention. It will also be understood that the guard may be employed without the use of the throwout switches, but the use of the 45 switch construction is preferable and will be adopted in the best structures where motor or other electric drives are used for driving the press mechanism.

What I claim is:—

50 1. The combination with a pair of rolls, of

a pivotally mounted guard normally extending across and between the rolls, said guard including a plate having oppositely disposed faces lying closely adjacent the peripheries of the rolls.

60

2. The combination with a pair of rolls, of a pivotally supported guard, said guard including a plate having angularly disposed faces extending between the rolls and adjacent the peripheries thereof, and a stop for 65 limiting the movement of the guard toward the rolls.

65

3. The combination with a pair of rolls, of a guard including a plate having a pair of angularly disposed faces normally extending adjacent the peripheries of the rolls, and widthwise thereof pivoted arms on which the plate is carried, and a stop for limiting the movement of the arms.

70

4. The combination with a pair of rolls, of a pivoted guard mounted to lie closely adjacent the roll surfaces for preventing the hands of an operator from being caught therebetween, said guard having a swinging movement to and from the rolls, and a circuit controller actuated by the contact of the guard therewith in its movement away from the rolls.

75

5. The combination with a pair of adjacent rolls, of a single guard comprising a plate having sides arranged to form a V, the sides normally extending across and closely adjacent the peripheries of each roll, and means for mounting the plate to have a movement toward and from the rolls.

80

6. The combination with a pair of rolls the peripheries of which are closely adjacent, of a pivoted guard plate having angularly disposed sides extending between the rolls and adjacent the peripheries thereof, a motor, a circuit therefor, and a switch operated by the contact of the guard therewith for cutting out the motor.

85

7. The combination with a pair of cylinders having an impression contact with each other, a guard plate having angularly disposed sides arranged so that it may be swung to place the sides between the cylinders and closely adjacent the peripheries thereof, and a stop for limiting the movement of the guard so as to keep the sides free of the cylinders.

90

In testimony whereof, I have hereunto set my hand.

HERMAN STUKE.
